ELIMINATION OF ATMOSPHERIC RADIO DISTURBANCES

Samuel M. Whisk, Brooklyn, N. Y.

Application August 25, 1937, Serial No. 160,775

9 Claims. (Cl. 250—20)

The invention here disclosed relates to the elimination and avoidance of disturbing atmospheric radio frequencies, such as heretofore loosely termed as "static".

Objects of the invention are to provide simple, practical and effective apparatus which will filter or ground out objectionable frequencies, readily adjustable to eliminate the disturbing frequencies and conversely, build up the desired signal frequencies and which apparatus will be relatively inexpensive for the results accomplished and be applicable generally to existing radio receiving equipment.

The foregoing and other desirable objects are attained by novel features of construction, combinations and relations of parts as hereinafter pointed out, illustrated in the accompanying drawings and broadly covered in the claims.

The drawings accompanying and forming part of the specification illustrate different practical embodiments and applications of the invention. It is appreciated, however, that changes and modifications of the present disclosure may be made, all within the true intent and broad scope of the invention.

Figure 1 is a diagrammatic view illustrating an embodiment of the invention utilizing power line energy.

Figure 2 is a perspective view of the complete atmospheric eliminator unit.

Figure 3 is a diagrammatic illustration of an embodiment employing a battery as the current source.

Figure 4 is an illustration showing the invention applied to aircraft use.

One of the features of the invention is a double antenna pickup system with special means for balancing and grounding out the disturbing effects.

In Figure 1, two separate antennas are indicated at 5, 6, connected respectively to contacts 7, 8, on insulating base 9.

The two antennas may be angularly related or in general parallelism, as indicated, and they may be as nearly alike as possible or have quite different values. In service one acts as a counterpoise for the other.

Both antenna leads 5a, 6a, are fully shielded as indicated at 10 and this double antenna shielding is grounded as close as practicable to the actual antennas, as indicated at 11.

Mounted on the base 9 is a discharge tube 12 having separate insulated anodes 13, 14, with terminals 15, 16, engaging base contacts 7, 8 and a single cathode or discharge plate 17 having

a terminal 18 engageable with contact 19 which is grounded at 20. The grounding terminal prong 18 is indicated as larger than the others and the contact socket 19 of a corresponding size so that the discharge tube can only be mounted on the base in this one relation.

From input terminals 7 and 8, leads 21 and 22 are shown extending to opposite ends of the two reversely wound radio frequency primary coils 23, 24. These reversed primary windings are shown connected at the center and as having a common ground at this point at 25. Extending from this intermediate common ground is indicated a potentiometer arm 26 adjustable over the potentiometer winding 27 bridged across the two primary windings and the antenna input leads 21, 22.

The secondary windings 28, 29 of the two R. F. transformers are shown connected together at the center at 30 and as having output leads 31, 20 32 extending to the input transformer 33 of the radio receiving set indicated generally at 34.

A potentiometer winding 35 is indicated bridged across the two secondary windings and the adjustable arm 36 for this potentiometer is indicated as grounded at 37.

The input leads 21, 22 are indicated as shielded at 38 with the two shields connected together at 39. Similarly, the output leads are indicated as shielded at 40 and these shields connected together at 41 and jointly connected to the input shields at 42. All transformer lead shielding is shown as having a short connection 43 with the arm 44 of a special grounding switch adjustable to engage a straight grounding contact 45, a contact 46 for grounding through capacity 47 or a contact 48 for grounding opposite ways through both capacity 49 and inductance 50.

The special discharge tube 12 is indicated as shielded in a shielding compartment or container 40 and the R. F. transformers and potentiometers are indicated as shielded in a special shielding compartment or container 52. All the several parts may be contained in a metallic shielding case illustrated particularly at 53, Figure 2. In the latter view, the special grounding switch is shown located centrally on the front of the case with controls 26a and 36a for the two potentiometers at opposite sides of the same. This view also shows the shielding compartment for the discharge tube as having a window 54 through which any glow effect of this tube may be observed.

Where current supply for the receiver is taken from a power line, such as indicated at 55, Fig-

55

ure 1, a power filter is provided embodying inductance or choke coils 56 in opposite sides of the line located in separate shielding chambers 57 and each coil adapted to be grounded at either 5 or both ends through capacities 58 by grounding switches 59, 60, 61, 62.

The casing 53 for the complete unit is indicated in Figure 1 as suitably grounded at 63. The power transformer for the receiving set may 10 be of more or less conventional design, as indicated at 64.

Where a battery is employed as the power source, as indicated at 65 in Figure 3, the power filter may be employed as before, similar reference characters being used to denote similar 15 features, including the choke coils and switches for grounding through capacity.

Figure 4 is an illustration of the invention as applied to a two-way communication aircraft system. In this view the equivalent of the two 20 antennas is provided by antenna 5 and a counterpoise 66. Antenna 5 is led into the control box 67 by which it may be switched through line 68, or be cut back to the receiver 34, or vice versa. From the control box another lead 70 runs to the 25 atmospheric eliminator 54 and the counterpoise constituting in this instance the second antenna is led into this unit and connected in the same manner as the second antenna 6, Figures 1 and 3. With the control box 67 in Figure 4 the radio 30 system may be immediately switched over from transmitting to receiving, or vice versa, and in the receiving condition, the counterpoise is cut in as the second antenna for the atmospheric disturbance eliminator.

In all cases the receiver may be set for the desired signal and then the disturbance eliminator adjusted for rejecting or balancing out so-called static or atmospheric disturbances. Thus, there 40 is no need to first adjust the receiver, which would involve the possibility of losing the signal. With the double antenna disturbing frequencies ordinarily will come in on one and be balanced out or grounded, leaving the other clear and free to bring in the signal frequency. The discharge 45 tube is a low resistance tube enabling disturbances, which usually are of lower frequency, to pass to ground across the gap from one or the other plates 13, 14 to discharge plate 17. Radio disturbances coming in on the antenna shields 50 immediately ground out at 11 and any disturbing frequencies on the transformer shielding frequencies are grounded, through adjustment of the special grounding switch either direct or through 55 capacity or through both capacity and inductance, by way of grounding contacts 45, 46, 48. The R. F. transformer system is an all-wave balancing transformer combination. Those portions which are grounded by the potentiometers 60 are neutralized through such grounding. The discharge tube and the adjustable R. F. transformer take out electrostatic and electromagnetic disturbances. The power filter takes out inductive disturbances which may come in on the 65 power line. The antennas may be duplicates or be different, one acting as a counterpoise for the other. Both are shielded and grounded independently of the grounding of the rest of the shielding. By proper adjustment of the unit disturbances may be balanced out and grounded 70 even though of higher value than the signal frequencies.

If energy is picked up by the antennas, as from a nearby power line or the like, the discharge tube will glow and indicate this wrong condition.

This tube also may operate as a lightning arrester and may serve as a safety device when a common antenna is used both for receiving and transmitting and reception is begun when the switch is on for the transmitter.

The potentiometer adjustments serve also for volume control, particularly on short-wave reception, because of the sharp selectivity on high frequencies. To overcome fading effects, the operator ordinarily only needs to bring the radio 10 controls up to maximum sensitivity and then adjust the potentiometer of the atmospheric filter for volume and clear signal. The coils for the radio frequency transformers may all be wound on a single tube, thus making the structure in 15 effect a single all-wave, all-frequency transformer. The first potentiometer grounds parts of the radio frequency primary and the second potentiometer portions of the radio frequency secondary sections.

In aircraft installations the same shielding is employed such as shown in detail in Figures 1 and 3 and the elimination of disturbing frequencies is the same. The adjustment of the first potentiometer 26 grounds out portions of one side 25 or the other, thereby neutralizing disturbing frequencies in the primary windings. Similarly any disturbing frequencies transferred to the secondary windings are grounded and balanced out by adjustment of the second potentiometer 36. 30 Both these potentiometers are of the non-inductive type so as not to increase or decrease the inductive effects of incoming frequencies.

The four grounding or bucking switches 59, 60, 61, 62 at opposite ends of the chokes in the power 35 filters enable inductive or conductive disturbances coming in on the hot leg or on the neutral or grounded wire to be grounded at either the input or the output or at both ends of the choke coils, depending upon the character of such disturbances. This filter is thus in effect a "semi-tuned" filter.

What is claimed is:

1. In apparatus for elimination of atmospheric radio disturbances, a dual antenna system, a low resistance discharge tube having electrodes in connection with the two antennas and an electrode separated by gaps from said first mentioned electrodes and having a grounding connection, a radio frequency transformer having reversely wound primary and secondary sections, input connections from said first mentioned tube electrodes to oppositely wound sections of the primary, output connections from the oppositely wound secondary sections for connection with a 45 radio receiving set and potentiometers across the oppositely wound primary and secondary windings having adjustable grounding connections.

2. In apparatus for elimination of atmospheric radio disturbances, a dual antenna system, a low resistance discharge tube having electrodes in connection with the two antennas and an electrode separated by gaps from said first mentioned electrodes and having a grounding connection, a radio frequency transformer having reversely wound primary and secondary sections, input connections from said first mentioned tube electrodes to oppositely wound sections of the primary, output connections from the oppositely wound secondary sections for connection with a 60 radio receiving set, potentiometers across the oppositely wound primary and secondary windings having adjustable grounding connections, shielding for said transformer connections and an adjustable grounding switch for said shielding having 65 70 75 80 85 90 95 98 99 100

ing contacts for variously grounding said shielding.

3. In apparatus for elimination of atmospheric radio disturbances, a dual antenna system, a low resistance discharge tube having electrodes in connection with the two antennas and an electrode separated by gaps from said first mentioned electrodes and having a grounding connection, a radio frequency transformer having 10 reversely wound primary and secondary sections, input connections from said first mentioned tube electrodes to oppositely wound sections of the primary, output connections from the oppositely wound secondary sections for connection with a 15 radio receiving set, potentiometers across the oppositely wound primary and secondary windings having adjustable grounding connections, shielding for said transformer connections, an adjustable grounding switch for said shielding having 20 contacts for variously grounding said shielding, including direct grounding means, capacity grounding means and a combination of capacity and inductive grounding means.

4. In apparatus for elimination of atmospheric radio disturbances, a dual antenna system, a low 25 resistance discharge tube having electrodes in connection with the two antennas and an electrode separated by gaps from said first mentioned electrodes and having a grounding connection; a radio frequency transformer having reversely wound primary and secondary sections, input connections from said first mentioned tube electrodes to oppositely wound sections of the primary, output connections from the oppositely wound secondary sections for connection with a radio receiving set and potentiometers across the oppositely wound primary and secondary windings having adjustable grounding connections, said potentiometer for the primary sections having 30 an intermediate grounding connection between the oppositely wound sections of said primary.

5. In apparatus for elimination of atmospheric radio disturbances, a dual antenna system including 35 antenna leads, a low resistance discharge tube having electrodes in connection with the two antennas and an electrode separated by gaps from said first mentioned electrodes and having a grounding connection, a radio frequency transformer having reversely wound primary and secondary sections, input connections from said first mentioned tube electrodes to oppositely wound sections of the primary, output connections from the oppositely wound secondary sections for connection with a radio receiving set, potentiometers across the oppositely wound primary and secondary windings having adjustable 40

grounding connections and grounded shielding for the leads of said dual antennas.

6. In apparatus for elimination of atmospheric radio disturbances, a dual antenna system, a low resistance discharge tube having electrodes in connection with the two antennas and an electrode separated by gaps from said first mentioned electrodes and having a grounding connection, a radio frequency transformer having reversely wound primary and secondary sections, 10 input connections from said first mentioned tube electrodes to oppositely wound sections of the primary, output connections from the oppositely wound secondary sections for connection with a radio receiving set, potentiometers across the 15 oppositely wound primary and secondary windings having adjustable grounding connections and shielding casing for said discharge tube and transformer.

7. In apparatus for elimination of atmospheric 20 radio disturbances, a dual antenna system, a low resistance discharge tube having electrodes in connection with the two antennas and an electrode separated by gaps from said first mentioned electrodes and having a grounding connection, a radio frequency transformer having reversely wound primary and secondary sections, 25 input connections from said first mentioned tube electrodes to oppositely wound sections of the primary, output connections from the oppositely wound secondary sections for connection with a radio receiving set and potentiometers across the oppositely wound primary and secondary windings having adjustable 30 grounding connections, a shielding casing for said discharge tube and transformer and an adjustable grounding switch on said casing.

8. In atmospheric radio disturbance elimination, a dual antenna system including shielded antenna leads, a low resistance discharge tube connected therewith, an all-wave radio frequency transformer having reversely wound primary and secondary sections, neutralizing and grounding connections from the reversely wound primary sections of said transformer, shielded input and output connections for said transformer and means for variously grounding said shielding.

9. In atmospheric radio disturbance elimination, a dual antenna system including shielded antenna leads, a low resistance discharge tube connected therewith, an all-wave radio frequency transformer having reversely wound primary and secondary sections, shielded input and output connections for said transformer and adjustable grounding potentiometers bridged across said reversely wound primary and secondary sections.

SAMUEL M. WHISK.
